F. R. KIMBLE

GAS BROODER

Filed August 24, 1925

Fig. 1.

INVENTOR:
Frank R. Kimble;

BY G. E. Maynard.
ATTORNEY.

UNITED STATES PATENT OFFICE.

FRANK R. KIMBLE, OF VAN NUYS, CALIFORNIA.

GAS BROODER.

Application filed August 24, 1925. Serial No. 52,067.

To all whom it may concern:

Be it known that I, FRANK R. KIMBLE, a citizen of the United States, and resident of Van Nuys, Los Angeles County, State of California, have invented new and useful Improvements in Gas Brooders, of which the following is a specification.

This invention relates to chicken brooders and especially to gas burner brooders.

10 An object is to provide a gas brooder which is of very simple form, and is designed and constructed to obtain a high economy of consumption and is efficient in the combustion of the fuel so that no unburned gas escapes to the brooder chamber.

15 An object is to provide a brooder which is very effective in throwing the heat down toward the chamber floor.

Other objects and advantages will be made 20 manifest in the following specification of an embodiment of the invention here illustrated; it being understood that modifications, variations and adaptations may be resorted to within the spirit and scope of 25 the invention as it is here claimed.

Figure 1 is a plan; parts being broken away.

Figure 2 is a vertical central section.

30 A serious defect with forms of gas burning chicken brooders is that an objectionable degree of unburnt gas is given off because of improper combustion, and another objection is that too intense a heat beam is sometimes produced in a localized zone because of 35 an insufficient degree of ventilation immediately under the brooder hood where the chicks tend to congregate.

40 My present brooder includes a flat, conical top or hood 2, of suitable diameter, having on its lower side a central pad 3 of asbestos against which is secured a center plate 4. Bolts 5 pass down through the hood, the asbestos and the plate 4, which latter is engaged by nuts 6.

45 Below the nuts 6 is a crown or disc 8 adjustable on the bolts 5 to a desired position below the liner plate 4 so as to provide an air circulating space 10, which not only provides for flow of air currents around and over the crown 8 but also serves to keep flame from the hood 2 and plate 4, these therefore being protected and allowing use of thin metal in the large hood element and thus saving in cost of construction since this element will not be burnt up by the burner flame. Nuts 9 secure the crown in place.

The crown is supported directly on top of a burner head 11 having air holes 12 in its neck 13 which latter is screwed on the upper end of a gas supply pipe 14 extending up from the brooder house floor F, and having a regulating valve 15.

It will be seen that the burner discharges the gas for combustion close up to the bottom of the crown which, since it takes all 65 the burning contact with the flames, may be made of heavy plate or sheet metal and can be removed from time to time, as necessary.

From the above it will be seen that the crown not only protects the hood from the 70 flame but serves as a hot plate to complete combustion of all the gas from the burner, and serves, at the same time, to form an air circulation space under the hood proper, such as would not be the case if the burner 75 discharge directly toward or against the hood.

The heat, instead of being lost by passing up through the hood, is cast down by the 80 insulated central part thereof.

The device is of substantial structure and few parts and these can be packed, shipped and stored in nested, knock-down condition.

What is claimed is:

1. A chicken brooder including a hood, 85 a crown spaced under the center of the hood, and a burner on which the crown is supported and from which gas for combustion is delivered up against the crown.

2. A chicken brooder including a hood, 90 a burner below the hood, and a crown over the burner and spaced below the hood, whereby to form an air space below the hood and also form a hot plate for combustion of fuel, and a protective medium lining the 95 central portion of the hood and for reflecting down heat therefrom and reducing loss of heat by transmission through the hood.

3. A chicken brooder including a hood, 100 a set of bolts passing through the hood, a crown plate arranged on the bolts in adjustable, spaced position below the hood to form an air space therebelow, and a burner directly on which the crown is secured to directly receive flame of combustion therefrom.

4. A brooder including a hood, a set of bolts passing through the hood, a crown plate arranged on the bolts in adjustable, 110 spaced position below the hood to form an air space therebelow, and a burner on which the crown is secured to directly receive flame

of combustion therefrom, and a heat barrier secured on the lower face of the hood to protect the same and throw the heat down.

5. A brooder including a hood, a set of bolts passing through the hood, a crown plate arranged on the bolts in adjustable, spaced position below the hood to form an air space therebelow, and a burner on which

the crown is secured to directly receive flame of combustion therefrom, and a heat barrier secured on the lower face of the hood to protect the same and throw the heat down; the bolts having nuts for securing the crown and the barrier in place.

FRANK R. KIMBLE.
